UNITED STATES PATENT OFFICE.

ANTONE GARMO, OF PORTLAND, OREGON.

CARRIER BLOCK FOR LUMBER CARRIERS.

Application filed February 10, 1927. Serial No. 167,296.

This invention relates to carrier blocks for lumber carriers and has for an important object thereof the provision of a device of this character which will increase the amount of lumber which may be carried by the carrier.

A further object of the invention is to produce a device of this character so constructed that the lumber will be very firmly held in position thereon and there will not be the tendency of the lumber to slip when the load is lifted or dropped by the carrier that there is with the ordinary structure.

These and other objects I attain by the construction shown in the accompanying drawings, wherein for the purpose of illustration is shown a preferred embodiment of my invention and wherein:

Figure 1 is a sectional view through a lumber carrier having carrying blocks constructed in accordance with my invention;

Figure 2 is a section on the line 2—2 of Figure 1;

Figure 3 is a longitudinal sectional view 25 through the carrying block;

Figure 4 is a section on the line 4—4 of Figure 3.

Referring now more particularly to the drawings, the numeral 10 generally indicates the carrying rails of a lumber carrier, which are vertically adjustable to enable the load to be elevated from and deposited upon the ground. These carrying rails have inwardly directed flanges 11 which are engaged beneath cross bars which in turn support the lumber. In accordance with my invention, I provide a cross bar 12, preferably in the form of an inverted channel having castings 13 secured to the ends thereof and provided with vertically offset flanges 14 adapted to rest upon the flanges 11 of the carrying rails. While the offset portions are preferably provided by castings above referred to, these offsets may be produced upon the ends of the bar 12 in any suitable manner. The under surface of the flange 14 is preferably provided with a socket 15, for the reception of a rubber pad 16, which actually engages the carrying rails 11, and increases the grip of the flanges 14 thereon.

In the preferred construction herein illustrated, the arms 17 of the channel section 12 diverge downwardly. The base or channel engaging portion 18 of the casting 13 is provided in its upper surface with a

depression 19, preferably of slightly greater depth than the thickness of the base portion 20 of the channel member and upon which this base portion seats. Downwardly 60 diverging channel arm receiving grooves 21 are formed in this base section into which the channel arms may be slid by an endwise movement of the channel member. Securing elements 22 directed through the base 65 section of the channel member into the base section of the casting serve to prevent separation thereof.

It will be obvious that since the depression 19 is made of slightly greater depth than the thickness of the base 20 of the channel, the ribs 23 produced by the channel receiving grooves will extend slightly above the upper surface of the channel member and will, therefore, serve to hold against dislodgment 70 a facing strip 24, which may be of wood or other suitable material upon which the lumber to be carried will seat more firmly than it ordinarily will upon a metal surface. It will be obvious that by vertically offsetting 75 the ends of the bar, the carrying capacity of the carrier will be increased and that furthermore lumber cannot be knocked out of position with relation to the bar by a blow against the side thereof. In this connection, it is pointed out that in manipulating the lumber carrier into position over the load, the side members 25 from which the carrying rails 11 are supported, often come in contact with the lumber and with the present structure tends to disarrange the same 80 sufficiently to require re-loading thereof.

It will be obvious that a device of this character may be very cheaply and readily produced and will materially facilitate the loading of the carrier and increase the efficiency thereof. It will furthermore be obvious that certain changes can be made in the structure hereinbefore set forth without in any manner departing from the spirit of the invention and I accordingly do not limit myself to such specific structure except as 85 hereinafter claimed.

I claim:

1. A carrying bar for use with lumber carriers comprising an inverted channel bar and a pair of castings each having in its upper surface a socket for the reception of the base portion of the channel and being further provided with grooves receiving the ends of the arms of the channel, said castings each including a vertically offset out-

wardly directed flange adapted to engage the carrying rail of the lumber carrier.

2. A carrying bar for use with lumber carriers comprising an inverted channel bar and a pair of castings each having in its upper surface a socket for the reception of the base portion of the channel and being further provided with grooves receiving the ends of the arms of the channel, said castings each including a vertically offset outwardly directed flange adapted to engage the

carrying rail of the lumber carrier, the sockets of said castings being of greater depth than the thickness of the base of the channel bar whereby the castings and the upper surface of the channel bar combine to form sockets for the reception of the ends of a strip of anti-friction material applied to the upper surface of the bar.

In testimony whereof I hereunto affix my signature.

ANTONE GARMO.
